ATTORNEY

UNITED STATES PATENT OFFICE

102,220

DESIGN FOR A CHRISTMAS TREE HOLDER

Kenneth A. Bird and Edward E. Farley,
Pocatello, Idaho

Application March 24, 1936, Serial No. 61,770

Term of patent 14 years

To all whom it may concern:

Be it known that we, Kenneth A. Bird and Edward E. Farley, citizens of the United States of America, residing at Pocatello, in the county of Bannock and State of Idaho, have invented a new, original, and ornamental Design for a Christmas Tree Holder, of which the following is a specification, reference being had to the accompanying drawing, forming a part thereof.

We claim:—

The ornamental design for a Christmas tree holder, as shown.

KENNETH A. BIRD.
EDWARD E. FARLEY.
